UNITED STATES PATENT OFFICE.

ROYCE L. BEERS, OF DETROIT, MICHIGAN, ASSIGNOR TO DETROIT STOKER COMPANY,
OF DETROIT, MICHIGAN, A CORPORATION OF MICHIGAN.

STOKER.

Application filed January 19, 1925. Serial No. 3,522.

This invention relates generally to stokers and refers more particularly to that type in which a ram is employed for forcing the fuel into the furnace.

5 One of the essential objects of the invention is to provide the rams of such stokers with a simple driving mechanism in which yieldable means is preferably used for the purpose of preventing breakage of the parts 10 if an unusual obstruction is encountered by the ram during operation of the stoker.

Another object is to provide a stoker that is simple and compact in construction, efficient in operation and inexpensive to maintain.

With the above and other objects in view the invention consists in certain novel features of construction, combinations and arrangements of parts as will be more fully 20 described and particularly pointed out in the appended claims.

In the accompanying drawings;

Figure 1 is a vertical longitudinal sectional view through a portion of a stoker 25 embodying my invention.

Figure 2 is a vertical sectional view through the ram.

Figure 3 is a top plan view of the ram.

Figure 4 is a vertical sectional view 30 through the shoe.

Figure 5 is a top plan view of the shoe.

Figure 6 is a detail view of the wrist pin.

Heretofore rams of stokers have been provided with driving mechanism in which one 35 or more pins are adapted to be sheared off, if abnormal resistance is encountered by the rams, to prevent the parts of the stoker from being damaged. However this is objectionable for the reason considerable time 40 is required to replace a broken pin or member preliminary to resuming operation after the obstruction has been removed. With the present invention this objectionable feature is overcome by providing a permanent yieldable driving connection between the rams and pitman rods.

Referring now to the drawings in which like characters of reference designate corresponding parts throughout the several 50 views, the numeral 1 designates a ram case that opens into the furnace 2 and has a hopper 3. 4 is a pitman rod for reciprocating a suitable ram 5 in the case 1. Any suitable means (not shown) may be employed for actuating the pitman rod 4.

For the purpose of preventing the parts from being damaged in the event that the ram 5 encounters abnormal resistance in its movement, I have provided a yieldable construction which is sufficiently strong to operate the ram under ordinary conditions but which will give when the ram 5 encounters said resistance so that the actuating means (not shown) for the pitman 4 may continue to operate without damaging any of the stoker parts. To accomplish this I preferably position two concentric coil springs 6 and 7 respectively within the ram 5 between the head 8 thereof and the head 9 of a plunger or shoe 10 slidably engaging the inner walls of the ram. These springs may be formed of any suitable material such as steel. Jointly they will suffice to operate the ram under ordinary conditions. For connecting the ram 5 to the pitman rod 4 I preferably provide a suitable wrist pin 11 that extends through aligned circular openings 12 in the sides of the shoe 10 and engages aligned longitudinally extending slots 13 in the side walls of the ram 5. Thus, with this construction, power will be transmitted from the pitman rod 4 through the shoe 10 and springs 6 and 7 respectively to the ram 5 for operating the latter under ordinary conditions. However should the movement of the ram 5 be interrupted due to an obstruction or other cause, the movement of the pitman rod 4 and shoe 10 will be taken up by the springs 6 and 7 respectively which will permit the driving mechanism to operate while the ram is inoperative. Inasmuch as the springs 6 and 7 are concentrically arranged it will also be apparent that a standard form of ram having a relatively small diameter may be used and that the maximum strength is provided in a relatively small space.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim as my invention is:

1. In combination with a stoker for furnaces, provided with a hopper adapted to receive fuel and a ram case below and in communication with the hopper for receiv-

ing fuel therefrom, a ram mounted for reciprocation in said ram case for forcing the fuel into the furnace, a hollow shoe mounted for coaxial reciprocation within said ram, a pitman rod pivotally mounted within said shoe for imparting reciprocatory movement to said ram, and a spring positioned between said shoe and ram within the latter for normally preventing relative axial movement between the shoe and ram and for transmitting movement from the pitman to the ram, said spring being adapted to permit reciprocation of the pitman without movement of the ram and to absorb the thrust of the pitman upon the encountering of an unusual obstruction by said ram.

2. In combination with a stoker for furnaces provided with a hopper adapted to receive fuel and a ram casing below and in communication with the hopper for receiving fuel therefrom, a ram mounted for reciprocation in said ram casing for forcing the fuel into the furnace, a hollow shoe mounted for coaxial reciprocation within said ram, a pitman rod pivotally mounted within said shoe for imparting reciprocatory movement to said ram, and a spring positioned between said shoe and ram within the latter for normally preventing relative axial movement between the shoe and ram and for transmitting movement from the pitman to the ram, said spring being adapted to permit reciprocation of the pitman without movement of the ram and to absorb the thrust of the pitman upon the encountering of an unusual obstruction by said ram.

In testimony whereof I affix my signature.

ROYCE L. BEERS.
